CORN STRIPPING FORK

Charles W. G. Allender, Golden, Colo.

Application January 14, 1954, Serial No. 28,511

Term of patent 7 years

(Cl. D44—29)

FIG. 1.

FIG. 4.

FIG. 5.

FIG. 2

FIG. 3.

To all whom it may concern:
Be it known that I, Charles W. G. Allender, a citizen of the United States, residing at Golden, State of Colorado, have invented a new, original, and ornamental Design for Corn Stripping Fork, of which the following is a specification, reference being had to the accompanying drawing, forming a part hereof.

The dominant features of my design reside in those portions shown in full lines; specifically, the wider outer tines having substantially vertical edges in combination with the curvature of the tines as best shown in Fig. 2.

I claim:

The ornamental design for a corn stripping fork, as shown and described.
